(57) **CLAIM**

The ornamental design for a cord wrap as shown and described.

DESCRIPTION

FIG. 1 is a perspective view of a cord wrap showing my new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The cord wrap is characterized by an apparatus that has an elongate body with two opposing ends. Each of the opposing ends has a groove portion configured to house at least one portion of a cord.
